UNITED STATES PATENT OFFICE.

FERNAND STOFFEL, OF PARIS, FRANCE, ASSIGNOR TO VACUUM HAND BLOCKING COMPANY, OF NEW YORK, N. Y., A CORPORATION OF NEW YORK.

APPARATUS FOR SHAPING HATS.

Application filed May 22, 1922. Serial No. 562,639.

To all whom it may concern:

Be it known that I, FERNAND STOFFEL, a citizen of the Republic of France, and a resident of Paris, France, have invented certain new and useful Improvements in Apparatus for Shaping Hats; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In his U. S. Patent No. 1,080,731, the applicant described a process for rapidly shaping hats wherein the hats impregnated with sizing are softened by the effect of steam and then applied by the use of a tight elastic membrane and by means of a vacuum upon a mould in order to obtain the desired shape of the hat and to dry the same.

The present invention relates to an apparatus of a simple, practical and portable character whereby the above-indicated operations may be carried out, and obviating an expensive and complicated installation in this branch of manufacture.

In principle, the said apparatus comprises the following elements which are so combined and associated as to constitute a single device having a reduced size.

a.—A vacuum chamber serving as a base for a receptacle whose perforated top portion constitutes the support for the mould, and is connected through a conduit provided with a cock with the vacuum chamber; a row of gas jets or like heating means is provided below the said receptacle.

b.—A vacuum pump, actuated for example by an electric motor, whereof the suction end is connected with the said vacuum chamber and the delivery end with a compressed air storage reservoir.

c.—A water spraying device such as an ejector, which is connected on the one hand with the compressed air reservoir and on the other hand with a water tank, the water spray nozzle being caused to open into the said perforated receptacle supporting the mould.

The following description, together with the accompanying drawings which are given by way of example, sets forth an embodiment of this invention.

Fig. 1—1^a is a general elevational view of the apparatus.

Fig. 2—2^a is a plan view of the same, partially in section.

In the form of construction as set forth hereunder, the mould together with the hat (not shown) is disposed upon the table *a* constituting the top of a receptacle *b* which is strengthened by the hoops *b*¹ *b*² provided with the apertures *c*.

The receptacle *b* is mounted on the vacuum chamber *d* which communicates by the conduit *e* with the suction end of a compressor *f*, the latter being actuated by an electric motor *g* disposed above the same. The compressor discharges through the conduit *h* into a reservoir *i* constituting a muffler. The receptacle *b* and the vacuum chamber *d* are in communication through the conduit *j* provided with the cock *k*.

The reservoir *i* is connected through the conduit *l* provided with the three-way cock *l*¹ with an ejector *m* which serves to produce a water spray, the said ejector being connected through the conduit *n* having mounted thereon the cock *n*¹ with a water tank *p* having immersed therein the tube *n*. The cock *l*¹ is a three-way cock and serves to connect the conduit *l* with the outer air for a free discharge, or with the ejector *m* when it is desired to deliver sprayed water into the receptacle *b*. The latter may be heated by any suitable means, for example by a row of gas jets disposed below the receptacle *b*. The whole arrangement comprising the said elements is preferably mounted upon a common base *u*.

The operation of the said apparatus is carried out in the following manner:

The electric motor *g* is started, and the cock *l*¹ is opened to the outer air; the vacuum pump *f* produces a vacuum in the chamber *d*, and the reservoir *i* will act as a muffler; inasmuch as the section of the conduit *l* is smaller than that of the discharge conduit *h*, the air delivered will be stored up and compressed in the said reservoir. The hat treated with sizing is placed upon the mould and the latter is disposed upon the top surface of the receptacle *b*; the cock *l*¹ is then connected with the spray ejector *m*, and the cock *n*¹ is opened. The air stored up in the reservoir *i* will pass through the conduit *l* into the ejector *m* and will draw up water from

the tank *p* which becomes sprayed and is delivered through the nozzle *s*, Fig. 2, into the receptacle *b* wherein it is immediately transformed into steam, by reason of the high temperature given to the bottom of the receptacle *b* which is heated by the gas burners *q*. The steam escapes through the apertures in the top portion *a* and is supplied under a rubber sheet which is disposed upon the hat under operation so as to provide for the softening of the hat. When this is accomplished, the cock *n*¹ is closed and the cock *t*¹ is opened to the outer air, then the operation of shaping the hat is proceeded with by opening the cock *k*. By reason of the vacuum in the chamber *d*, the steam and air contained in the receptacle *b* and under the said rubber sheet will be at once drawn out through the conduit *j*, and a vacuum is instantly produced under the said sheet, which will now be applied tightly against the apertured top portion of the vacuum receptacle *a*, closing the apertures and forming a tight joint, and the said sheet is also brought down strongly upon the hat which is thereby caused to conform to the mould under the action of atmospheric pressure. This vacuum also aids in the drying operation in an energetic manner, by the rapid absorption of the moisture.

It is obvious that the said apparatus is susceptible of all desired modifications without departing from the principle of the invention; in particular, the water spray injecting device may consist of an independent apparatus such as a hand-operated spray device.

As observed in the drawings, an emptying cock for condensed steam is provided at the lower part of the chamber *d*.

What I claim is:

1. In a hat forming machine, a perforated hat form supporting table, a receptacle thereunder, a spray device to supply water to the interior of the receptacle, means exterior of the receptacle to heat the same and convert water in the receptacle into steam, and means to exhaust the receptacle.
2. In a hat forming machine, a vacuum chamber, a perforated table supported above said chamber, a receptacle beneath said table said table forming the top of the receptacle, a heating device interposed between said chamber and receptacle, means to connect said chamber and receptacle, a compressed air reservoir, a compressor included between vessel and chamber, and a water jet operated by compressed air from

said reservoir and connected to said receptacle.

3. In a hat forming machine, a receptacle having a perforated top forming a table, a vacuum chamber supporting said receptacle, a compressed air reservoir, a compressor interposed between said chamber and reservoir, a water tank, an ejector connected to said tank and reservoir and discharging into said receptacle, and valved means connecting said receptacle and chamber.

4. In a hat forming machine, a receptacle having a perforated hat-form supporting top, a plurality of perforated concentric top supporting hoops in said receptacle, means to heat said receptacle, means to exhaust the receptacle and means to inject a water spray into said receptacle to produce steam therein.

5. In a hat forming machine, a receptacle having a perforated hat supporting top, a vacuum chamber beneath the receptacle and supporting the same, a gas heater between said chamber and receptacle, a compressed air reservoir, a compressor interposed between said chamber and reservoir, a motor mounted over said compressor to drive the latter, a tank, an ejector connected to said reservoir and arranged to draw liquid from said tank and discharge it into said heated chamber, a valve-controlled connection between said chamber and receptacle, and a liquid draw-off cock at the bottom of said chamber.

6. In a hat forming machine, a steam generating receptacle having a perforated top for supporting a hat-form, means for introducing water into the receptacle under pressure, means for heating the latter to convert the water into steam simultaneously with its entrance into the receptacle, and means to exhaust the receptacle independently of the injecting means.

7. In a hat forming machine, a steam generating receptacle having a flat, perforated, top portion, means for highly heating the receptacle, heat conducting members inside the receptacle, means for spraying water into the latter against the conducting means, whereby steam is generated in the receptacle simultaneously with the entrance of the spray therein, and means to exhaust the receptacle independently of the injecting means.

In testimony that I claim the foregoing as my invention, I have signed my name hereto.

FERNAND STOFFEL.
